UNITED STATES PATENT OFFICE.

HENRY E. MORTON, OF MUSKEGON HEIGHTS, MICHIGAN.

HEAD FOR DRAW-CUT SHAPERS.

1,218,951.

Specification of Letters Patent. Patented Mar. 13, 1917.

Application filed February 18, 1916. Serial No. 79,155.

To all whom it may concern:

Be it known that I, HENRY E. MORTON, a citizen of the United States of America, residing at Muskegon Heights, in the county 5 of Muskegon and State of Michigan, have invented certain new and useful Improvements in Heads for Draw-Cut Shapers; and I do hereby declare the following to be a full, clear, and exact description of the invention, such as will enable others skilled in 10 the art to which it appertains to make and use the same.

This invention relates to a draw cut shaper and especially to a movable type of 15 head adapted to be used on said shaper or other similar tools such as metal planers and the like in which a cutting tool is drawn back and forth over the work acted upon or the work is moved back and forth with 20 respect to the cutting tool which may be relatively stationary. It is the object and purpose of my invention to provide a device which on one motion of the tool with respect to the work or of the work with 25 respect to the tool will take a roughing cut while upon the return movement another tool will operate upon the work to make a finishing cut, in this manner greatly reducing the time heretofore used in machining 30 metal parts. A further object of the invention consists in the provision of a tool of this character in which a great number of heads may be used at different times for different characters of work. For an un- 35 derstanding of the construction by which these ends together with others not specifically enumerated are attained, reference may be had to the accompanying drawings, in which;

40 Figure 1 is a side elevation of a draw cut shaper having my invention applied thereto.

Fig. 2 is a side elevation of the mechanism showing the head carrying the tool for accomplishing the finishing cut.

45 Fig. 3 is a front elevation of the head.

Fig. 4 is a plan view thereof; and

Fig. 5 is a side elevation similar to Fig. 2 but illustrating a different type of head.

Like reference characters refer to like 50 parts throughout the several views of the drawing.

The frame of the shaper indicated at 1 has positioned in front thereof a bed 2 upon which the work is laid. This bed may be 55 adjusted vertically by any suitable adjusting means shown at 3, it being supported

at its front end by a suitable support 4 which may also be adjustable for various positions of the bed. The ram 5 of the shaper is mounted for movement back and forth 60 adjacent the upper portion of the frame 1, the mechanism for operating the ram not being shown in the drawings as it forms no part of the invention. The front end of the ram 5 carries a supporting head 6 which 65 may be attached in any suitable manner to the ram, and held in position by set screws 7. The supporting head is located horizontally and is provided on its front face with a T-shaped slot 8 receiving a bolt head 9 70 of such formation as to lie within the wider portion of the slot and have a part project forward a short distance into the narrower portion thereof. The present construction shows tool supports known ordinarily as 75 clapper boxes which are carried by two bolt heads 9 located in the slot 8. In front of each bolt head 9 a saddle 10 is positioned, each of which has an adjusting screw 11 passing horizontally therethrough, the ends 80 of the adjusting screws in the two saddles being joined by a screw threaded connection as indicated in Fig. 3. Each saddle is formed with an upwardly extending part 12 on which is hung a swiveling block 13 85 which at its upper end is provided with a slot 15, a bolt 16 extending from the projection 12 through the slot and receiving a nut on its end as shown.

Each swiveling block is formed with a cy- 90 lindrical forward extension 14 and it is on this extension that the tool supports or clapper boxes 17 and 17^a are located. The two tool supports in the present head are somewhat of the same formation having slots 95 formed in their sides in which cutting tools 18 and 19 are mounted, these tools being retained in position by means of set screws 20. The cutting tool 18 carried by the clapper box 17 is located with its cutting edge in 100 the rear while the tool 19 carried by the opposite clapper box 17^a has its cutting edge positioned directly opposite. A bolt 21 passes through the clapper box, saddle, swiveling block and bolt head as indicated 105 in dotted lines in Figs. 1 and 2 and on its outer end carries a nut 22, the parts in this manner being secured together. The clapper box 17^a has a plate 23 interposed between it and the nut 22, this plate, however, not 110 being used with the opposite clapper box as shown.

The clapper box 17 has a limited pivotal movement on the extension 14 about the transverse pin 24 so that its tool 18 on the forward working stroke thereof, will move 5 slightly to the rear but on the return stroke when no work is done by it may be moved forward as it moves over the work without acting thereagainst. The opposite clapper box 17^a is similarly pivotally mounted on 10 a pin 24^a shown in dotted outline but it will be observed that this pin is located adjacent the front side of a clapper box while pin 24 is located adjacent the rear side so that the pivotal movements of the two clapper boxes 15 are the reverse of each other, and when the tool carried by one is working to make a cut on the work located on bed 2 the tool carried by the other is passing freely over the work and does not act thereon. Accordingly, with the forward stroke of the ram 20 the cutting tool 19 takes a cut from the work while on the return stroke the tool 18 takes its cut, in this manner causing the ram to operate upon the work in both its forward 25 and rearward strokes. It will be evident that with one of the tools set for a roughing cut and the other a finishing cut, a piece of work may be entirely finished without requiring the double passage of the ram and 30 the tools carried thereby over the work as has been required heretofore. The clapper box 17^a is provided with the bearing plate 23 to serve as a stop against too extreme movement of the clapper box during its 35 working stroke.

Each cutting tool 18 and 19 may, if desired, be provided with a channel like positioning member 25 through one flange of which passes a set screw 26, its end bearing 40 against the tool. With one of these attached adjacent the upper end of a tool, it may be located in a desired position, in a clapper box 17 or 17^a the member 25 seating against the upper end and properly positioning the tool 45 which may thereafter be removed for grinding or the like and replaced in exactly the same position.

In Fig. 5 I have shown a modified form of head in which a clapper box 17^b similar in 50 most respects to the one indicated at 17, but extending a distance lower, and pivoted on a similar pin 24 is provided on its under face with a horizontal slot 27, this slot extending substantially the full width of the 55 box and adapted to receive a wider finishing tool 28 which is held in position by set screws 29. One of the salient features of my invention and one of great importance is that various types of heads may be used 60 interchangeably on the ram and in Fig. 5 I have illustrated a different kind of head which may be used in place of the one shown in Figs. 1 and 2.

Changes in detail of construction may be 65 resorted to without departing from my in-

vention defined in the appended claims. Accordingly I do not wish to be restricted to the exact disclosure made but consider myself entitled to all modifications in structure falling within the scope of the claims defining the invention. 70

I claim:—

1. In combination, a supporting head having a T-slot in a face thereof, a pair of bolt heads positioned in the slot, a saddle in 75 front of each bolt head, a swiveling block located in front of each saddle having a slot in its upper portion, a bolt passing from the saddle through the slot, a nut on the bolt, a tool holding support on each swiveling 80 block, each mounted on a horizontal pin extending through the block, the pin in one block passing through the support adjacent its rear side and above the middle thereof, while the pin in the other block passes 85 through the other support adjacent its front side and above the middle thereof, a tool carried by each support the cutting edges thereof being located opposite to each other and a bolt extending through each bolt 90 head, saddle, swiveling block and tool holder and provided with a nut at its forward end for securing said parts together in fixed relation to each other and the supporting head. 95

2. In combination, a supporting head, a pair of bolt heads carried by the supporting head, a saddle in front of each bolt head, an adjusting device extending through each saddle, said devices being adjustably connected together, a swiveling block positioned 100 in front of each saddle having a slot in its upper portion, a bolt extending through said slot and carried by the saddle, a nut on the bolt, a clapper box carried by each swiveling block, said clapper boxes being mounted on 105 horizontal axes one located above the middle and adjacent the rear face of a clapper box and the other above the middle and adjacent the front face of the other clapper box, means for detachably securing a cutting tool 110 in each clapper box with the cutting edges thereof positioned oppositely, a bolt extending through each bolt head, saddle, swiveling block and clapper box, and a nut on the front end of each bolt for securing said 115 bolt head, saddle and swiveling block together and fixing them on the supporting head. 120

3. In combination, a supporting head, a pair of bolt heads carried by the supporting head and movable lengthwise of or removable therefrom, a bolt extending forward from each bolt head, a saddle in front of each bolt head, adjusting screws extending horizontally through each saddle, a connection between the meeting ends of the adjusting screws, a swiveling block in front of each saddle through which the associated bolt extends, a clapper box mounted on an extension to each swiveling block, a hori- 125 130

zontal pin passing through each clapper box and extension, said pins both being located above the middle of the clapper boxes and with one pin located adjacent the rear face 5 of a clapper box and the other adjacent the front face of the other clapper box, and a nut on the forward end of each bolt for

securing the parts together, substantially as described.

In testimony whereof I affix my signature.
HENRY E. MORTON.
